GAME APPARATUS

Stephen Feltin and Vernon E. Turner, Cleveland,
Ohio

Application June 5, 1940, Serial No. 338,978

1 Claim. (Cl. 273—127)

This invention relates to game apparatus, and more specifically, to a novel game goal adapted to be used in playing such games as table hockey and the like.

An object of this invention is to provide a new and novel goal, which is simple, inexpensive, and rugged in construction, and adapted to be used in playing various games.

Another object is to provide a goal characterized by the provision of readily adjustable barriers provided along the goal, thus adding new selective features to the game, and making provisions for differences in playing skill of the various players.

Other and further objects of the invention will be apparent during the course of the following specification.

In the drawing accompanying the specification and forming a part of this application:

Figure 1 is a front elevational view of our new and improved goal with the barrier removed,

Figure 2 is a view corresponding to Figure 1 with the barrier inserted,

Figure 3 is a broken perspective view through a corner of the goal,

Figure 4 is an enlarged sectional view taken on the line 4—4 of Figure 2,

Figure 5 is an enlarged sectional view taken on the line 5—5 of Figure 2, while

Figure 6 is a view of a hockey stick and puck.

The apparatus disclosed herein is adapted to be played on a game board or other flat surface, preferably having walls around the sides thereof, and provided with markings and other indicia delineating various playing boundaries and areas, in accordance with well recognized practices. As such features are well recognized in the art it was considered to be unnecessary to include the same in this application.

The numeral 10 refers generally to our new and improved goal, comprising a framework having a front portion formed of a pair of spaced vertically extending members 11 connected along the top by a horizontally extending member 12, while a pair of spaced frame members 13 extending rearwardly from the bottom of the vertically extending frame members 11 are connected by a rear frame member 14. Extending from the upper portion of the vertically positioned frame members 11 to the outer ends of the frame members are brace members 15.

The goal frame work, above described, may be made of any suitable material such as wood or metal. We have found it advantageous to use thin strips of metal for such purpose. The goal

10 may be secured to the game board or table by any suitable means, such as wood screws 16 adapted to be placed in apertures 17 in the frame members 13 for securing them to the board or table in an obvious manner.

10 A goal enclosure in the form of a net 18 formed of woven netting or other suitable material extends rearwardly from the goal 10. A series of small apertures 19 are provided along the frame members 11, 12, 13, and 14, while a string 20 serves to bind the net 18 to the frame members, as shown in Figures 1, 2, and 3. Any other suitable means may be used for securing the net 18 to the goal frame.

15 Along the lower front surfaces of the vertically extending frame members 11 are provided a pair of guideways 21 extending upwardly substantially one-half the length of the members 11. The guideways 21 open towards the center of the goal 10 permitting a barrier 22, connecting the members 11 to be inserted and removably retained therein, as shown in Figure 2. The guideways 21 preferably are positioned and arranged in such manner as to permit the barrier 22 to be lowered 25 into the guideways 21, firmly retained therein, and yet readily lifted therefrom. If desired the barrier 22 may be formed of the same material as that used in the goal 10, although any suitable material may be used.

20 Along the lower rear portion of the barrier 22 horizontally extending guideways 23 are provided, while a gate 24 slidably mounted in the guideways 23, serves to open and close an aperture 25 along the lower margin of the gate 24. One end 25 of the gate 24 is bent rearwardly forming a handle 26 adapted to be grasped by the hand in sliding the gate 24 along the guideways 23. The position and arrangement of the gate 24 and the guideways 23 permits the gate 24 to be quickly 30 and easily reciprocated and leaves the front of the barrier 22 free from any obstructions which might tend to interfere with unobstructed playing of the game.

35 When the goals herein described are to be used 40 in playing a table hockey game a small round puck 27 formed of wood or other suitable material, and a small hockey stick 28 may be used in a manner to simulate a conventional hockey game on ice, the puck 27 being advanced along the table 45 by the hockey stick 28 in an obvious manner.

A game using the devices described herein may be played by two or more players in a manner simulating a regular hockey game played on ice, the puck 27 being advanced along a playing surface and into the goals in a well known manner.

It may be found advantageous when only two players are engaged in the game to have the barrier 22 in the position illustrated in Figure 2 wherein the barrier is retained in position by the guideways 21. However, when the game is played by four players, preferably with two on each side, the barrier 22 may be removed from the goal 10 and one player on each side may be designated as a goal tender. The game is then played in a manner somewhat similar to that when two players are used.

The slideable gate 24 provides an optional feature for the game, permitting it to be readily opened or closed to suit the desires of the contestants. It may be found desirable when the players are of substantially equal ability to have the gate 24 opened, as it adds to the scoring opportunities and general interest in the game. If the players are not of substantially equal ability, it may be desirable to have the gate 24 closed on the goal belonging to the less skilled player, thereby giving the less skilled contestant a slightly better opportunity to compete with the other players on an equal basis.

Obviously games other than table hockey may be played with the goals and apparatus disclosed herein and it is not intended to limit the use of

the goals to any particular game. It will be apparent to those skilled in the art that our invention may be changed, used, or modified, without departing from the spirit of the invention, and that our embodiment of the invention disclosed herein is illustrative only, and our invention is not limited thereto.

We claim:

An adjustable goal for game apparatus adapted to be played on a surface, comprising: a pair of spaced upwardly extending frame members joined by a connecting member spaced from said surface thereby forming an opening permitting a movable object to be advanced therebetween, a detachable barrier connecting said pair of frame members and extending at least partially the distance from said surface to said connecting member, the same being provided with a cut-out portion permitting said movable object to be advanced therethrough, guideways disposed horizontally along the back of said barrier along the top and bottom of said cut-out portion, and a gate slideable horizontally in said guideways for selectively covering and uncovering said cut-out portion, for the purposes described.

STEPHEN FOLTIN.
